UNITED STATES PATENT OFFICE.

JOSEPH D. KING AND MATTHEW A. BURNS, OF MENOMINEE, MICHIGAN.

HAT-FASTENER.

SPECIFICATION forming part of Letters Patent No. 595,483, dated December 14, 1897.

Application filed August 9, 1897. Serial No. 647,600. (No model.)

To all whom it may concern:

Be it known that we, JOSEPH D. KING and MATTHEW A. BURNS, citizens of the United States, residing at Menominee, in the county 5 of Menominee and State of Michigan, have invented certain new and useful Improvements in Hat-Fasteners; and we do hereby declare the following to be a full, clear, and exact description of the invention, such as will 10 enable others skilled in the art to which it appertains to make and use the same.

Our invention relates to improvements in hat-fasteners for ladies' hats; and it consists in the novel devices hereinafter described and 15 claimed.

Referring to the accompanying drawings, in which the same parts are designated by the same letters of reference throughout the several views, Figure 1 represents a horizontal 20 section of a hat provided with our improved fastener, the said section being taken on the line 1 1 of Fig. 2, looking upward, as indicated by the arrows. Fig. 2 is a longitudinal sectional view of the same, taken on the line 25 2 2 of Fig. 1; and Fig. 3 is a detail perspective view of the front fastener.

A designates the hat, which may be of the usual construction for ladies' wear and may be of straw, as shown, or of any other suitable 30 material. At the back of the hat a flat piece of metal B is secured to the inner band A' of the hat in any suitable manner, such as by sewing. The inner edge of the said piece of metal B is bent toward the center of the 35 hat, as at b. To the inner edge b of the piece B is hinged, as at b', a second flat piece of metal C, which is slightly bent, as shown in Fig. 2, and has secured thereto any number 40 of fingers or prongs c, like the prongs of a hair-pin, which may be made straight or "wavy," as may be desirable.

Through the front portion of the hat is passed a rod D, having a head d, like the head on a hat-pin, and from a point near the head 45 to the opposite end the said rod is flattened, as at d'.

A metal tube or sleeve E is arranged to slide on the flattened portion d' of the rod D, the opening through the said sleeve being of 50 such shape and size that the said sleeve E will not turn upon the said rod. The flattened portion of the rod D is screw-threaded along

its edges near its end, as at d², and is provided with a nut D', formed in the shape of the head d.

The sleeve E has a square portion E' formed at its central part for a purpose to be hereinafter explained, and the said sleeve is provided with a number of curved fingers e, the two smallest ones being one on each side of the square portion E' and the other fingers e being arranged at intervals along the sleeve E, the largest ones at the ends thereof, as shown in Fig. 3.

The rod D is stuck through one side of the 65 hat, and the sleeve E is placed upon the flattened portion thereof. The end of the rod is then passed through the other side of the hat, and the nut D' is screwed thereon to hold the said rod in position.

A flat spring F is secured to the back of the piece B and extends toward the front of the hat, where it is bent around the square portion E' of the sleeve E, as at f.

A flat piece F' is secured to the spring F 75 and extends beneath the bent-over part f thereof near the square part E' of the sleeve E and acts as a check to prevent the said sleeve E and rod D from being accidentally turned.

The hat is placed upon the head by allowing the fingers c to open, as shown in dotted lines in Fig. 2, and then inserting the said fingers in the hair, like a hair-pin, after which the hat is brought down upon the head and 85 the rod D turned in the direction of the arrow in Fig. 2 by its head d. This will also turn the sleeve E and cause the fingers e to enter the hair and hold the front part of the hat in place, and the flat piece F' and the 90 spring F, inclosing the square portion E' of the sleeve E, will prevent the said sleeve from being accidentally turned, as hereinbefore explained.

By this construction we produce a hat-fas- 95 tener which is very simple in its action and free from locks or other holding devices on the outside of the hat and which will hold the hat securely in place upon the head.

The hat is easily placed upon the head and 100 secured in place and as easily removed by turning the head d, a slight pressure being sufficient to cause the square portion E' to slip over the end of the piece F', when the

fingers *e* may be turned out of the hair. The hat may then be removed by withdrawing the fingers *c* from the hair.

Having thus described our invention, what 5 we claim, and desire to secure by Letters Patent of the United States, is—

1. In a hat-fastener, the combination with a flattened rod passing through the hat, and means for holding the said rod in the hat, of 10 a sleeve mounted upon the flattened portion of the said rod and having a squared portion; curved fingers secured upon the said sleeve; means whereby said sleeve may be turned; and a flat spring-arm bearing on the squared 15 portion of said sleeve and adapted to hold the same against accidental turning, substantially as described.

2. In a hat-fastener, the combination with a rod passing through the hat; a sleeve mounted 20 on said rod; curved fingers secured to the said sleeve; means whereby said rod and sleeve may be turned, and means for holding the said sleeve against accidental turning; fingers *c* hinged to the inner edge of the hat 25 and adapted to engage the hair and close upon said sleeve, substantially as described.

3. In a hat-fastener, the combination with a rod passing through the hat; a sleeve mounted on said rod; curved fingers secured to the

said sleeve; means whereby said sleeve may 30 be turned; of a plate *B* secured to the inner side of the hat; a spring-arm secured to the said plate *B* and partially inclosing the said sleeve; and fingers hinged to the said plate *B* and adapted to pass through the hair and 35 to close upon the said sleeve, substantially as described.

4. In a hat-fastener, the combination with a rod passing through the hat; a sleeve having a squared portion mounted on the said rod; 40 curved fingers secured to the said sleeve, and means whereby said sleeve may be turned; of a plate *B* secured to the inner side of the hat; a curved spring-arm *F* secured to said plate *B* and partially inclosing the squared portion 45 of said sleeve; a plate *F'* secured to the said spring-arm and adapted to engage the said squared portion of the said sleeve; and fingers hinged to the said plate *B* and adapted to pass through the hair and to close upon 50 the said sleeve, substantially as described.

In testimony whereof we affix our signatures in presence of two witnesses.

JOSEPH D. KING.
MATTHEW A. BURNS.
